CLAIM

The ornamental design for a reclosable debris bag for pool cleaners, as shown and described.

DESCRIPTION

FIG. 1 is a top plan view of a reclosable debris bag for pool cleaners showing my new design;
FIG. 2 is a bottom plan view thereof;
FIG. 3 is a front elevational view thereof;
FIG. 4 is a left side elevational view thereof;
FIG. 5 is a right side elevational view thereof;
FIG. 6 is a rear elevational view thereof;
FIG. 7 is an enlarged top plan view of the self-locking closure as shown in FIGS. 1 and 2, the bag is omitted for convenience of illustration;
FIG. 8 is a front elevational view of FIG. 7 as shown in FIG. 3; and
FIG. 9 is a rear elevational view of FIG. 7.
The crosshatching shown partially in various views represents woven mesh material and is understood to be uniform for all bag surfaces.
